(57) **CLAIM**

The ornamental design for an accessory for vehicle exterior, as shown and described.

DESCRIPTION

In use, the vehicle accessory can be affixed to the exterior of a vehicle to modify the appearance thereof. The accessory is preferably affixed to the decklid of a Ford Mustang™ having the decklid configuration of the 2005–2007 models.

FIG. 1 is a perspective view of an accessory for vehicle exterior, wherein the broken lines showing the vehicle are provided for illustrative purposes only and form no part of the claimed design;

FIG. 2 is a front elevation view thereof;

FIG. 3 is a rear elevation view thereof;

FIG. 4 is a side elevation view thereof, the right and left sides being identical;

FIG. 5 is a top plan view thereof; and,

FIG. 6 is a bottom plan view thereof.
